(57) **CLAIM**

The ornamental design for an inverter, as shown and described.

DESCRIPTION

FIG. 1 is a front perspective view seen from bottom and right side of an Inverter showing our new design;

FIG. 2 is a front perspective view seen from top and left side thereof;

FIG. 3 is a back perspective view seen from top and right side thereof;

FIG. 4 is a back perspective view seen from bottom and left side thereof;

FIG. 5 is a top plan view thereof;

FIG. 6 is a bottom plain view thereof;

FIG. 7 is a left-side elevational view thereof;

FIG. 8 is a back plan view thereof;

FIG. 9 is a right-side elevational view thereof; and,

FIG. 10 is a front plan view thereof.
